UNITED STATES PATENT OFFICE.

WILLIAM KENNEDY PETERS, OF NEW YORK, N. Y., ASSIGNOR TO THE GLEASON-PETERS AIR PUMP COMPANY, OF SAME PLACE.

DESIGN FOR A PUMP-STAND.

SPECIFICATION forming part of Design No. 32,454, dated April 3, 1900.

Application filed October 30, 1899. Serial No. 736,322. Term of patent 7 years.

To all whom it may concern:

Be it known that I, WILLIAM KENNEDY PETERS, a citizen of the United States, and a resident of New York city, in the county of New York and State of New York, have invented a certain new, useful, and original Design for Pump-Stands, of which the following is a specification.

This invention relates to a new, useful, and original design for a pump-stand.

The characteristic feature of the design may be described as comprising a base, a separated or divided pillar, and a top plate surrounding the pillar, the pillar connecting the base and top.

The drawings which accompany and form part of this specification illustrate a pump-stand of my design.

Figure 1 represents a side elevation of my invention, and Fig. 2 a plan view of the same.

Similar letters of reference refer to similar parts in the two views.

The base A is in the shape of an elongated quatrefoil or cross with rounded corners a. From the base a pillar B, flat in cross-section, extends upward, being enlarged at the base and curving inward toward the top plate D.

The pillar is divided by an arched central opening C, extending upward from the base to near the upper end of the stand. c is a 30 web half-round in cross-section, running around on each face of the pillar and flush with said opening C.

D is the top plate, rectangular in form, set at an angle to a vertical line through center of the stand. This plate is flat on its upper surface, both ends terminating in enlarged ovals d, perforated as shown.

An air-pump stand shaped as described and comprising a base, pillar, and top plate, all 40 having the general outline shown, makes a neat and ornamental device for the purpose intended.

Having thus described my invention, what I claim as new and original is as follows: 45

The design for a pump-stand substantially as shown and described.

Signed at New York, in the county of New York and State of New York, this 26th day of October, A. D. 1899.

WILLIAM KENNEDY PETERS.
